UNITED STATES PATENT OFFICE.

CHARLES H. BERGQUIST, OF OKMULGEE, OKLAHOMA, ASSIGNOR OF ONE-HALF TO
EMERY A. LOCKE.

BRACE FOR WELL-DRILLING TOOLS.

Application filed January 31, 1924. Serial No. 689,699.

To all whom it may concern:

Be it known that CHARLES H. BERGQUIST, a citizen of the United States, residing at Okmulgee, in the county of Okmulgee and State of Oklahoma, has invented new and useful Improvements in Braces for Well-Drilling Tools, of which the following is a specification.

This invention relates to tool braces especially adapted for use in drilling oil and gas wells.

The tool braces now on the market are not readily adjustable for use in connection with tools of different diameters and because the body of the brace is usually formed of two telescopic sections the brace does not possess the desired strength or simplicity.

Therefore, an important object of this invention is to provide a tool brace which may be readily and conveniently applied to a string of tools and the floor circle or track during the unscrewing or screwing up of the tool joints and which may be quickly and easily adjusted for use in connection with tools of different diameters.

A further and equally important aim of the invention is to provide a tool brace which will effectively act to hold the derrick circle or track to the derrick floor during the unscrewing of the joints.

A further object is to provide a brace of the character specified which is of highly simplified construction, durable in use and cheap to manufacture.

Other objects and advantages will be apparent during the course of the following description.

In the accompanying drawing forming a part of this application and in which like numerals are employed to designate like parts throughout the same,

Figure 1 is a perspective illustrating the improved brace applied to a string of tools and the derrick circle or track.

Figure 2 is a side elevation of the brace applied, the track being shown in section.

Figure 3 is a perspective of an attaching dog embodied in the invention.

In the drawing wherein for the purpose of illustration is shown a preferred embodiment of the invention, the numeral 5 designates a string of tools consisting of a plurality of sections threadedly connected as

at 6 and having square portions 7 for engagement by relatively stationary and movable wrenches 8 and 9 respectively.

Figure 1 illustrates that the wrench 8 is engaged with a stop 10 at one end of the derrick circle or track 11 and is held against turning in one direction thereby. The wrench 8 holds the lower portion of the string of tools stationary while the upper joint is loosened by the wrench 9.

As is well known in the art the handle of the wrench 9 is engaged by what might be said to be a driving member 10 having a manually operated actuating lever 12. It will be seen that the operation of the lever 12 results in the travel of the driving member 10 whereby the wrench 9 is turned for breaking the joint.

The parts thus far described are old and well known in the industry and the invention forming the subject matter of this application consists of a rigid one piece body 14 having one end flattened to provide a tool engaging portion 15. However, it is to be understood that the inner end of the body 15 may be provided with any suitable tool engaging means without departing from the spirit of this invention.

The outer portion of the rigid one piece body 14 is provided along its upper edge with notches or teeth 17 for securing an attaching dog 18 in the desired position on the body. Figure 3 plainly illustrates that the shank 20 of the dog 18 is curved longitudinally and is provided with a longitudinal slot 21 which freely receives the outer portion of the body so that the dog may be quickly positioned at the desired point on the body.

In carrying out the invention the attaching dog 18 is provided with an approximately L-shaped base 22 which as illustrated in Figure 2 embraces one of the flanges of the track and therefore securely and positively connects the rigid body 14 to the track. It might be said that one end portion of the shank 20 co-operates with the L-shaped base 22 in the formation of a socket for the reception of the flange of the derrick circle. A suitable lug 25 is carried by the outer portion of the body 14 and co-operates with a handle 26 in holding the attaching dog on the body.

In operation the inner end of the brace is engaged with the tool as illustrated in Figure 1 and the attaching dog is adjusted on the brace so that the L-shaped base will embrace the flange of the track whereby the brace is mounted in the manner illustrated in the drawing. It is believed to be clear that the brace is engaged with the tool between the upper and lower wrenches and in this case the side strain on the tool incident to the use of the wrenches will cause the brace to fulcrum on the track and thereby tighten the connection between the track and the brace. Briefly, the greater the strain on the brace, the tighter the connection between the brace and the track. This positively prevents the brace from getting out of place during the unscrewing of the joint.

A further and equally important advantage resulting from fulcruming the brace on the upper side of the track resides in the fact that the track is securely held in position on the derrick floor by the brace. It is thus seen that the brace not only maintains the tool in a proper position but also aids substantially in holding the track in position.

A change in the diameter of the tool may readily be provided for by an adjustment of the attaching dog on the body 14. This may be quickly and conveniently done. A tool constructed in accordance with this invention may be quickly and conveniently applied and adjusted owing to the fewness of parts and it will be seen that this fewness of parts not only permits the device to be expeditiously employed but also permits the device to be economically manufactured. Figure 2 illustrates that the body of the brace is of one piece construction and consequently is able to withstand the severe strain during the use of the wrenches. The body 14 is sufficiently stout in cross sectional area and is of a metal having the necessary strength to resist strain during use.

Attention is especially directed to the fact that the hardened steel flat tool engaging portion 15 may when necessary be conveniently dressed and sharpened by the drilling crew without being removed from the derrick. It is not necessary to take the brace to the shop and sharpen or renew the tool engaging portion when the same becomes dull or worn and consequently much time and expense is saved. It might be added that the tool braces now on the market are in most cases provided with more or less troublesome tool engaging portions and they wear rapidly so that frequent repair and replacement is necessary.

Having thus described the invention what is claimed is:—

1. A tool brace comprising a rigid one piece body having one end provided with means for engaging a string of tools and the

other end provided with spaced notches, and an attaching dog having a shank freely receiving said body and selectively seated in one of said notches, said attaching dog being provided with a substantially L-shaped derrick circle embracing portion, said rigid one piece body being adapted to extend over and fulcrum on the derrick circle. 70

2. A tool brace comprising a body provided with means for engaging a string of tools, and an attaching dog having a shank freely receiving and adjustable on said body and provided with a derrick circle embracing portion, said body being adapted to extend over and engage the derrick circle. 75

3. A tool brace comprising a body having its inner end provided with tool engaging means, and a dog carried by the outer portion of the body and having a derrick circle engaging member adapted to connect the body to the derrick circle, said body being adapted to extend over and engage said derrick circle. 80

4. A combined tool and derrick circle brace comprising a body having tool engaging means, and an attaching member adjustably carried by the outer portion of the body and having an approximately L-shaped derrick circle engaging and embracing portion, said body being adapted to extend over and engage a derrick circle and being provided with means to hold said attaching member in an adjusted position. 90

5. A tool brace comprising a rigid one piece body having its upper-edge portion provided with notches, an attaching dog having a shank freely receiving said body and adapted to be selectively received in one of said notches, said dog being provided with derrick circle engaging means adapted to connect the derrick circle to the body, and means to limit the endwise movement of said shank on said one piece body. 100

6. A tool brace comprising a body having tool engaging means and having a series of notches, and an attaching dog adapted to be selectively engaged in one of said notches and having derrick circle engaging means, said body being adapted to extend over and engage a derrick circle. 110

7. A tool and derrick circle brace comprising a rigid body adapted to extend over a derrick circle, and a derrick circle engaging dog adjustable on the body whereby the effective length of the body may be varied, one end of the brace being provided with means for engaging a string of tools, said dog being provided with an angularly directed terminal portion adapted to engage an underface of the derrick circle. 115

8. A tool and derrick circle brace comprising a body having tool engaging means and adapted to extend over and engage a derrick circle, and a dog carried by the body and having means to engage an underface 120

- of the derrick circle whereby tool pressure on the body tightens the connection of the dog with the derrick circle.
9. A well tool and derrick circle brace comprising a body adapted to extend over and fulcrum on a derrick circle, and means co-operating with the body to securely grip the derrick circle, one end of the body being provided with tool engaging means.
10. A tool brace comprising a body having one end flattened and sharpened to provide a single transversely extending sharp-ened edge adapted to bite into a string of tools whereby the body is securely connected to the string of tools.
11. A tool brace comprising a body having one end sharpened to define an edge adapted to engage a string of tools, and means carried by the other end of the body for anchoring the same, said edge constituting the sole tool engaging means of the brace.

CHARLES H. BERGQUIST.
